(57) CLAIM

The ornamental design for a paint spray gun, as shown and described.

DESCRIPTION

FIG. 1 is a first perspective view of a paint spray gun according to the present invention;

FIG. 2 is a second perspective view of the paint spray gun of FIG. 1;

FIG. 3 is a back view of the paint spray gun of FIG. 1;

FIG. 4 is a first side view of the paint spray gun of FIG. 1;

FIG. 5 is a top view of the paint spray gun of FIG. 1;

FIG. 6 is a second side view of the paint spray gun of FIG. 1;

FIG. 7 is a bottom view of the paint spray gun of FIG. 1; and,

FIG. 8 is a front view of the paint spray gun of FIG. 1.
